US00D613029S

(12) United States Design Patent
Krumholz et al.

(10) Patent No.: US D613,029 S
(45) Date of Patent: * Apr. 6, 2010

(54) CANDY

(75) Inventors: Lynn Krumholz, Sparta, NJ (US);
Brent Anderson, Lincoln Park, NJ (US)

(73) Assignee: Mars, Incorporated, McLean, VA (US)

() Term: 14 Years

(21) Appl. No.: 29/290,330

(22) Filed: Nov. 20, 2007

(51) LOC (9) Cl. 01-01

(52) U.S. Cl. D1/127

(58) Field of Classification Search D1/100, D1/106, 115, 121, 125, 127-130, 199; D25/138; 426/517, 115, 121, 129, 130, 144, 273, 274, 426/303, 414, 518, 104, 803; 428/20; D21/386; D24/101, 104; D28/8.1
